DESIGN FOR A TOOTHBRUSH

John Tutrani, Brooklyn, N. Y.

Application September 19, 1944, Serial No. 115,365

Term of patent 3½ years

(Cl. D9—2)

To all whom it may concern:

Be it known that I, John Tutrani, a citizen of the United States, residing at Brooklyn, in the county of Kings and State of New York, have invented a new, original, and ornamental Design for a Toothbrush, of which the following is a specification, reference being had to the accompanying drawing, forming part thereof.

Fig. 1 is an elevational view of one side of a toothbrush embodying my new design;

Fig. 2 is a plan view thereof showing the inside face; and

Fig. 3 is an elevational view of the other side of the brush shown in Fig. 1, on a slightly reduced scale.

I claim:

The ornamental design for a toothbrush, substantially as shown.

JOHN TUTRANI.
